CLOSURE DOOR ASSEMBLY FOR CONCRETE
MIXERS OR AGITATORSRobert M. Henderson, Springfield, Vt., assignor
to Worthington Pump and Machinery Corpora-
tion, Harrison, N. J., a corporation of Delaware

Application September 1, 1950, Serial No. 182,660

4 Claims. (Cl. 259—161)

1

This invention relates generally to transit type concrete mixers and more particularly to a closure door for the end opening thereof which will allow the mixer to operate as an agitator or provide means for converting a transit mixer to an agitator.

In the construction field it has been found that ready mixed concrete can be delivered by transit type truck mixers which usually consist of a truck frame having a rotatable drum thereon which is provided with a single end opening through which the mixed concrete is discharged.

Where the distances traveled by the mixer are relatively short, it has been further found that it is more efficient to utilize a central mixing plant system for pre-mixing the ingredients and allowing the mixers to act merely as agitators during the transfer of the mixed concrete to the site where it is to be used.

Where the distances are longer however, other methods are provided such as supplying the ingredients from some central point to the mixer and mixing them while the mixer is in transit, termed transit mixed concrete, or mixing the ingredients supplied to the mixer from some central point after the mixer has arrived at the site where it is to be used, termed job-mixed concrete.

The present type of transit mixers now on the market are generally of the type adapted to perform the transit mixed or job mixed type of operation, in that the end openings of the rotatable drums are usually adapted to receive some type of combined hopper and closure member where means for charging, agitating and discharging of varying quantities of concrete may be prepared, such for example as the combined hopper and closure member shown in my Patent No. 2,489,885, issued November 29, 1949.

When adapted to perform the transit mixed or job mixed type of operation, it has been found that the mixers when used as agitators must carry a lesser amount of mixed concrete than the rotatable drum capacity allows for, because of various difficulties such as, grit getting into the seals between the rotatable and non-rotatable portions of the hopper and closure members, spillage, loss of water etc., which occurs when greater quantities are used.

The present invention contemplates a means for replacing the combined hopper and closure door with a full closure door whereby transit mixers adapted to perform the above mentioned transit mixed or job mixed type of operation may be converted over to an agitator or to show a

2

construction for an agitator in which the rotatable drum will be capable of operating at full capacity.

Accordingly, it is an object of the present invention to provide a closure door assembly for the end opening of agitators or transit mixers.

It is another object of the present invention to provide a full closure door adapted to be rotatable with the rotatable drum for a transit type concrete mixer or agitator.

It is another object of the present invention to provide a rotatable closure door which is adapted to replace the combined charging hopper and closure member of a transit mixer whereby it will be converted to an agitator.

It is a further object of the present invention to provide a rotatable closure door which is adapted to replace the combined charging hopper and closure member of a transit mixer to convert it into an agitator, which is adapted to coact with the same operating means formerly imparting movement to the combined hopper and closure member.

With these and other objects in view, as may appear from the accompanying specification, the invention consists of various features of construction and combination of parts, which will be first described in connection with the accompanying drawings, showing a closure door assembly for concrete mixers or agitators of a preferred form embodying the invention, and the features forming the invention will be specifically pointed out in the claims.

In the drawings:

Figure 1 is an end view of the mixer showing the relationship of the invention to the operating parts.

Figure 2 is a side elevation showing the invention in its closed position in the end opening of a mixer.

Figure 3 is a partial section taken through the pivoting means provided for the invention.

Referring more particularly to the drawings, Figures 1 and 2 show the elevated material transfer end of a mixing drum 1 having an axial end opening 2. The drum 1 is mounted for rotation in any suitable manner on the main frame (not shown) of the mixing machine. About the opening 2 is an annular flange 3 which is connected to the drum by some suitable means such as welding. The annular flange 3 is adapted to mount a removable drip ring 4 thereon to provide a closure surface for a closure door 5, all of which is clearly shown in Figure 2 of the drawings. A removable drip ring is shown and described in

my pending application, Serial No. 165,148, filed May 31, 1950.

Rotatable closure door

The closure door 5 is a flat circular plate-like member of substantially the same diameter as the removable drip ring 4, which it contacts on its inner surface when the closure door is moved into engagement with the axial end opening 2 to close it, as is clearly shown in Figures 1 and 2 of the drawings. It is understood that while this type of surface-to-surface engagement is shown that other types of surfaces such as cone-shaped deep rings and dished shaped closure doors might be utilized for this purpose.

The means for making the closure door 5 rotatable is clearly shown in Figure 3 and include an opening 5' which receives therein a door hub 6.

Door hub 6 is a cylindrical member having a diameter slightly less than said opening 5' and provided with a door hub flange 7 about the upper portion thereof formed integrally therewith. It is mounted on the closure door 5 through the opening 5' so that the flange 7 will abut the outer surface of the closure door 5 to provide means for fixedly connecting the hub 6 to the closure door 5, such as by bores 8, having bolts 9 passing therethrough and nuts 10 for locking the flange 7 to the closure door 5. The door hub 6 provides means for rotatably mounting the closure door 5 and one end of an elongated shaft 11, the other end of said shaft will provide means for flexibly mounting the closure door to a door support 12 which is in turn connected to a suitable operating mechanism to be hereinafter described.

Thus, door hub 6 is provided with an axial bore 13 into which fits one end of the shaft 11. The upper end of said bore 13 is provided with an enlarged recess 14, to receive therein the inner race 15 of a bearing of the transverse type, the outer race 16 thereof being rotatably separated from the inner race 15 by ball type bearings 17. A first annular shoulder 18 formed on the shaft 11 will abut the outer race 16 and will prevent the shaft 11 from being thrust too far into the bore 13 thus reducing any additional end friction that might develop and in addition provides means for holding the bearing in the recess 14. The first annular shoulder 18 will be held in position adjacent the outer race 16 by suitable means such as a split ring holding member 19 fixedly connected to the door hub 6 by suitable means such as bolts 20 and lock washers 21, all of which is clearly shown in Figure 3 of the drawings.

Figure 3 further shows split ring 19 as having passages 22 which are provided with any suitable type of grease connection 23 of which there are many well known types in the open market whereby lubrication for the rotatable portions above described may be provided.

Door support

The door support 12 provides means for mounting the closure door 5 and rotatable assembly above described and for connecting the closure door 5 to suitable operating means for moving it into and out of engagement with said axial end opening 2.

Thus, Figures 1 and 3 clearly show the door support 12 as a substantially elongated channel-shaped member disposed in a horizontal plane across said closure door 5. In the medial portion thereof is an elliptical opening 24 which receives the other end of shaft 11 therethrough. A second

shoulder 25 will be provided on the shaft 11 between the split ring 19 and the inner surface 26 of the door support 12. The second shoulder 25 will abut the inner surface of the door support 12 about the elliptical opening 24 to prevent the closure door 5 from coming into contact with the door support at any time.

Shaft 11 also passes through a door adjusting plate 27 which is a substantially block-like rectangular member, lying in the channel 28 formed on the outer surface of the door support 12.

The shaft 11 extends past the channel 27 and is provided with means for flexibly mounting it to the door support 12, by a spring member 29 which abuts the door, adjusting plate 27 at one end and an adjusting nut 30 at the other end threadably mounted on the end 21 of the shaft 11. A locking nut 32 is provided to hold the adjusting nut in position, all of which is clearly shown in Figures 1 and 3 of the drawings. The spring 29 allows the closure door 5 to flex inwardly and outwardly as the door support 12 is moved or when the mixing drum 1 is in operation and the closure door 5 is rotating therewith.

The door adjusting plate 27, is further shown in Figure 1 as having elliptical bores 33 thereon which receive bolts 34 threadably engaging the channel 28 and locking nuts 35 therethrough, thus when the closure door 5 is mounted for engagement with the drip ring 3, it may be adjusted in the horizontal plane by sliding the adjusting plate 27 and shaft 11 passing therethrough back and forth until the desired position is secured and then locking it in place by means of bolts 34 and locking nuts 35.

The ends 36 and 37 of the door support 12 extend past either side of the closure door 5 and are provided with trunnions or cam following members 38 therein which provide means for connecting the door support 12 to the operating mechanism for moving the door support 12 and the closure door 5 connected thereto into and out of engagement with the axial opening 2.

Operating mechanism

One type of operating mechanism for moving the closure door 5 into and out of engagement with the axial opening 2 is shown in Figures 1 and 2 of the drawings, as substantially identical with that type shown and described in my prior Patent No. 2,489,885, it being understood that while this type of frame and operating mechanism is shown that other similar types of controls could be utilized with the present invention.

Accordingly, a frame 40 is positioned about the end of the drum opening 2. The frame has two upright members 41 and 42 spaced on each side of the opening 2 which are rigidly attached to the main frame (not shown) of the mixer. A horizontal member 43 above the opening joins the two spaced uprights 41 and 42.

Mounted on the frame may be any suitable type of mechanical system having proper toggle action such as a worm and wheel arrangement so that the closure door 4 may be moved to any desired position. Such type of mechanical system is shown in the present application.

Thus, a horizontal rocker shaft 44 is pivotally supported between the spaced uprights 41 and 42 just below the horizontal member 43 of the frame 40. Two operating arms 45 and 46, have their respective upper ends fixedly connected to the rocker shaft 44 so that when one or the other of said operating arms are turned the operating arms 45 and 46 will both be pivoted

about the axial line of the rocker shaft 44, as is clearly shown in Figure 1 of the drawings.

Accordingly, means are provided for moving one of said operating arms 45 which includes linkage arms 47a and 47b. Linkage arm 47b is connected at 48a to a worm and wheel nut 49 which is fixedly mounted on one of the spaced uprights 41. Linkage arm 47a is connected to the other end of linkage arm 47b and will be moved thereby. It is in turn connected at 48b to the operating arm 45. A handwheel 50 is provided for rotation of the worm and wheel nut 48, to actuate the nut 48 which in turn actuates lever arms 47a and 47b to move the operating arm 45. Since the operating arm 45 is fixedly connected to the rocker shaft 44 both the operating arms 45 and 46 will be moved inwardly and outwardly of the axial opening as the handwheel is rotated. All of which is clearly shown in Figures 1 and 2 of the drawings.

The lower end of the operating arms 45 and 46 will be engaged by linkage shafts 51 and 52. Linkage shafts 51 and 52 have adjustable ends 53 and 54 respectively, for adjusting the length of the linkage shafts 51 and 52 as desired.

Linkage shafts 51 and 52 pass through each of the legs of U-shaped brackets 55 and 56 which are identical in construction and which constitute the immediate means for connecting and moving the door support 12 as is hereinafter described.

Shoulders 57 are provided in each of the linkage shafts 51 and 52, to abut the inner leg of the respective brackets 55 and 56 and will force the said brackets outwardly when the linkage shafts 51 and 52 are moved by the operating arms 45 and 46 to which they are connected, on rotation of the handwheel 50 as above described. A yieldable connection between the outer legs of the brackets 55 and 56 and the ends 58 and 59 of the linkage shafts 51 and 52 respectively comprising springs 60 and 61 loosely mounted about the linkage shafts 51 and 52 and threaded locking means 62 and 63, so that the reverse movement of the handwheel 50 will move the brackets inwardly, all of which is clearly shown in Figures 1 and 2 of the drawings.

Since the linkage shafts 51 and 52 each pass through both legs of the U-shaped brackets 55 and 56, they will be moved substantially in one plane and will be prevented from imparting undesired twisting to the door support 12. In addition, the spring members 60 and 61 will provide flexibility in the operating mechanism.

The brackets 55 and 56 are provided with bearing surfaces 64 so that the trunnions or cam following members 38 on the ends of the door support 12 may be mounted therein to lie in a horizontal plane across the axial opening 2 of the mixing drum.

Between the U-shaped brackets 55 and 56 and the ends 36 and 37 of the door support 12 are cam plates 65 and 66. Each of the cam plates 65 and 66 are L-shaped having the base portions 67 and 68 thereof connected to the uprights 41 and 42 respectively, and the arm portions 69 and 70 extending perpendicularly therefrom between the ends of the door support 12 and the U-shaped brackets. Cam slots 71 are formed on each of said cam plates 65 and 66 so that the trunnion or cam following members 38 may ride in said slots and be supported by the cam plates 65 and 66. The cam slots 71 will provide a path wherein when the linkage shafts 51 and 52 cause the U-shaped brackets 55 and 56 to be moved as above

described. The cam following members 38 will be moved outwardly, first parallel to the axial line of the drum and then upwardly, away from the opening and inwardly, in the reverse thereof, substantially identical with the movement shown and described in my prior Patent No. 2,489,885.

A vent valve 72 is provided on the closure door 4 to allow for the escape of air when the mixing drum 1 is filled with the ingredients forming the mixture, a side opening (not shown) generally being provided on the mixing drum 1 for this purpose. The vent valve 72 will be opened by sliding vent closure arm 73 pivotally connected at 74 away from the opening until the loading operation is completed and it is desired to place the mixer into operation, all of which is clearly shown in Figure 1 of the drawings. It will be understood that while this type of venting means is shown that other types embodying the same idea may be utilized for this purpose.

While one form of the invention has been shown and described, it will be understood that the invention is not to be limited to the specific construction and arrangement of parts but that they may be widely modified within the invention defined by the claims.

What is claimed is:

1. In a concrete mixer including, a rotatable drum with an axial opening at one end for material transfer purposes, a frame straddling said opening, an operating mechanism connected to said frame having a manually operable handwheel for operating a worm and wheel unit, and lever means operated by said worm and wheel unit, and a pair of cam plates attached to said frame on each side of said opening having cam slots thereon, the combination with said operating means of, closure support, cam following means fixedly connected to said closure support mounted in said cam slots and connected to said operating means to allow said closure support to be moved towards and away from said opening, a shaft flexibly connected to said closure support in the medial line thereof, a closure plate, a hub member fixedly connected to said closure plate, a bore in said hub having an enlarged recess in the upper end thereof, means to coact with said recess for rotatably connecting the hub member to said shaft to rotatably mount said closure plate on the closure support, said closure plate adapted to engage said axial opening when the closure support is moved towards the axial opening, and means mounted on said closure support and connected to said shaft to adjustably position said shaft and closure plate connected thereto in the horizontal plane.

2. In the combination as claimed in claim 1 wherein the means coacting with the enlarged recess to rotatably connect the hub member to the shaft includes, a transverse bearing mounted in said enlarged recess, a shoulder on said shaft to abut the bearing, and a split ring in fixed relationship with said hub member mounted about said shoulder to position the shoulder adjacent said bearings and to hold the hub member and closure plate on said shaft.

3. In the combination as claimed in claim 1 wherein the means to adjustably position said shaft and closure plate in the horizontal plane includes, an adjustable plate adapted to receive said shaft therethrough slidably mounted on the closure support, elliptical bores in said adjusting plate on either side of said shaft, and threaded means to lock said adjusting plate to the closure

support after the shaft and closure plate are in position.

4. In a concrete mixer including, a rotatable drum with an axial opening at one end for material transfer purposes, a frame straddling said opening, an operating mechanism connected to said frame having a manually operable hand-wheel for operating a worm and wheel unit, and lever means operated by said worm and wheel unit, and a pair of cam plates attached to said frame on each side of said opening having cam slots thereon, the combination with said operating means of, a closure support transversely disposed with respect to said axial opening, cam following means fixedly connected to said closure support mounted in said cam slots and connected to said operating means to allow said closure support to be moved towards and away from said opening, a non-rotatable support means connected to said closure support, and closure means rotatably mounted on said support means adapted to engage said axial opening when the closure support is moved towards the axial open-
